UNITED STATES PATENT OFFICE.

JOHN M. MARLIN, OF NEW HAVEN, CONNECTICUT.

REVOLVING FIRE-ARM.

SPECIFICATION forming part of Letters Patent No. 367,821, dated August 9, 1887.

Application filed May 12, 1887. Serial No. 237,927. (No model.)

To all whom it may concern:

Be it known that I, JOHN M. MARLIN, of New Haven, in the county of New Haven and State of Connecticut, have invented a certain 5 new and useful Improvement in Revolving Fire-Arms, of which the following is a specification.

My invention relates to revolving fire-arms; and it consists in certain improved constructions and combinations of the several parts thereof, substantially as hereinafter described and claimed.

In the drawings, Figure 1 is a side elevation, partly in section, of a revolving fire-arm 15 constructed according to my invention. Fig. 2 is an enlarged view of a portion of Fig. 1, showing details of the mechanism more plainly. Fig. 3 is a lower side view of the portion of the arm shown in Fig. 2 complete, or not sectioned.

A is the frame and handle of the arm, which is to be provided with lock and trigger mechanism in the usual manner; but these parts are omitted from the drawings, as they form no 25 part of my present invention.

B is the barrel of the arm.

C is the revolving many-chambered cylinder. The frame A has a forwardly-extending part, a, beneath the cylinder, provided with 30 one half of a hinge in the shape of two leaves or plates, a' a', Fig. 3. The other half of the hinge consists of two leaves or plates, b' b', connected to and projecting downwardly from the barrel B. A pin, p, passes through these 35 four plates a' a' b' b' transversely from side to side and forms the pivot of the hinge. This pin is in the form of a headed bolt, with a screw-thread cut on the end and a blind or covered nut screwed onto its thread to form 40 a head on that end. These heads clamp or bind into the leaves or plates a' a', so as to carry or turn the pin p with them at all times in the operation of the hinge, as hereinafter described. The pin p has a transverse slot, p', 45 cut in one side of it just opposite the space between the plates b' b' of the hinge. Into this space is fitted the lifter L, consisting of a nearly circular disk turning freely on the pin p, which passes through its center. This lifter 50 is provided with a finger, l, projecting upward into the space behind the stem of the shell-extractor, as shown.

The cylinder C is mounted and revolves upon a tubular pin, e, projecting rearwardly from just beneath the barrel B, and is held in place 55 by a shoulder formed in the usual manner to the lower side of the latch b', which is upon a rear end of the barrel-extension b. The latch b' is of the ordinary construction, turning upon the pivot p', and locks the barrel to the stud 60 a' on top of the frame, in the usual manner. The spider c', which pushes out the empty shells from the cylinder-chambers, is of the ordinary form, and is located in a recess in the rear end of the cylinder and attached to 65 the rear end of the stem c', which extends forward through the bore of the cylinder pivot-pin e to the finger l of the lifter. The stem c' is provided with a shoulder, c', against which the spiral spring s bears at one 70 end, and at the other against the rear end of the chamber in the cylinder, as shown. This spring thus always keeps the spider c' seated in its recess in the cylinder, and by its pressure against the lifter-finger l, through stem c', 75 keeps the lifter, with relation to the barrel parts, in the position shown in Figs. 1 and 2 until the other parts come into operation, as hereinafter described.

In order to force out the extractor when desired, by means of the lifter L, the following described mechanism is employed: In the lower side of the lifter a chamber, e, is cut, of the form shown in Figs. 1 and 2. In this chamber a swinging latch, e', is mounted. This 85 latch has a round pivotal end, e'', fitting a corresponding part of chamber e, on which it swings or pivots. This pivotal end of the latch (formed of steel) is made slightly larger than the corresponding part 90 of chamber e, and is slotted through transversely and longitudinally, as shown, and then sprung together and placed in the chamber, when its expansion gives a frictional bearing of the latch in turning, which keeps it in 95 any given position until moved by external force. The opposite end of the latch has a nose, e', on one side, which bears against pin p as the latter turns with the frame of the arm, and a stud, e'', on the other side, made with a 100 square shoulder on its rear edge and a beveled shoulder, e'', on its front edge. This stud e'' is so proportioned that when the nose e' comes opposite the slot p' in pin p the latch e'

may be swung upward and withdraw the stud entirely within the periphery of the lifter L, and when the other parts of pin p come against the nose e³ the stud will be projected 5 out beyond this periphery. The slot is so arranged in pin p as only to allow the nose to enter it when the barrel is tipped upon the frame, as shown in Figs. 1 and 2. Thus when the barrel is closed and locked upon the frame 10 by latch b², the stud part e⁴ of latch e¹ will always be forced out beyond the periphery of the lifter L, as shown.

On the extreme forward end of frame-extension a is formed a square nose or shoulder, 15 a³, close to the periphery of lifter L, and on the lower side of the barrel is also attached a projecting nose or shoulder, b³, close to the periphery of the lifter.

The operation of the mechanism is as follows: When the barrel is locked to the frame, 20 the nose a³ of the frame and the projecting stud e⁴ of the lifter are at some distance apart, as shown in Fig. 3. The unlatching of the barrel from the frame and tipping it down 25 causes the nose a³ of the frame to travel along the edge of the lifter L until it comes in contact with the square shoulder of stud e⁴, as shown in Figs. 1 and 2; but as the pin p moves with the frame this movement has also brought the 30 slot p' in the pin opposite the nose e³. From this point the continued tipping down of the barrel revolves the lifter with the frame in the barrel part of the hinge, and the finger l of the lifter forces the extractor and its stem c² backward, throwing out the empty shells. 35 When this has been done, the beveled part e⁵ of stud e⁴ comes against the barrel-nose b³, which forces the stud e⁴ within the periphery of the lifter and releases the latter from the 40 nose a³ of the frame. The spring s then throws the extractor back into its normal position in the cylinder, carrying the lifter back to the position, in relation to the barrel, shown in Figs. 1 and 2. When the barrel is swung in

the opposite direction and locked to the frame, 45 the revolution of the lifter on pin p forces out the stud e⁴ from the lifter, and it is ready to act as before.

It will be observed that the cam shape of the pin p enables it to act on the latch e¹ to 50 force the stud end of the latter out of the lifter; also, that the latch swinging on a pivot beyond or in front of the pivot-pin p of the frame, causes the pressure of the nose a³ of the frame to tend to hold the latch in engagement with 55 the latter, and prevents its slipping off prematurely.

What I claim as new and of my invention is—

1. The combination of the barrel B, the frame provided with nose a³ and hinged to the 60 barrel by pin p, the lifter L, provided with finger l and revolving on said pin, with the latter made cam-shaped within the lifter, the latch e¹, mounted in the lifter, bearing against the cam-shaped portion of said pin and provided with stud e⁴, arranged to be projected into and withdrawn out of the path of nose a³ of the frame as the latter turns on its hinge, 65 and the extractor actuated by finger l during said movement, substantially as described. 70

2. The combination of the barrel B, the frame provided with nose a³ and hinged to the barrel by pin p, the lifter L, provided with finger l and revolving on said pin, with the latter made cam-shaped within the lifter, the 75 latch e¹, pivoted in the lifter on the opposite side of its pivot from nose a³, bearing against the cam-shaped portion of said pin, and provided with stud e⁴, arranged to be projected into and withdrawn out of the path of nose a³ 80 of the frame as the latter turns on its hinge, and the extractor actuated by finger l during said movement, substantially as described.

JOHN M. MARLIN.
